CLAIM

The ornamental design for a telephone set, as shown and described.

DESCRIPTION

FIG. 1 is a front, top and right side perspective view of a cradled telephone set, showing our new design; FIG. 2 is a top and left side perspective view thereof; FIG. 3 is a right side and back perspective view thereof. The solid black coloration shown in the figures is intentional to represent actual, effectual contrast coloring of the surfaces so treated in accordance with established office standards.

FIG. 1

FIG. 2

FIG. 3
